UNITED STATES PATENT OFFICE.

JOSEPH A. MANAHAN, OF NEW YORK, N. Y.

SASH-BALANCE.

SPECIFICATION forming part of Letters Patent No. 625,580, dated May 23, 1899.

Application filed January 23, 1899. Serial No. 703,100. (No model.)

To all whom it may concern:

Be it known that I, JOSEPH A. MANAHAN, a citizen of the United States, residing in New York, borough of Manhattan, in the county 5 and State of New York, have invented new and useful Improvements in Sash-Balances, of which the following is a specification.

By means of this invention a window can be automatically or easily operated, as set 10 forth in the following specification and claims and illustrated in the annexed drawings, in which—

Figure 1 is a front elevation of the window, parts being sectioned. Fig. 2 is a section 15 along x x , Fig. 1. Fig. 3 is a section along y y , Fig. 1. Fig. 4 is a section along z z , Fig. 1. Fig. 5 is a detail view of the bracket for the lower sash.

To the upper sash 1 is secured a brace or 20 bracket 2, having a neck portion 3 and an arm 4. From arm 4 a rod 5 extends downwardly and passes through lock 6. This lock is a sleeve having a longitudinal bore or passage and a transverse cut or bore. Into the 25 transverse cut is placed pivot 7, which has a perforation corresponding with the perpendicular bore or perforations of the lock portion 6, so that rod 5 passes through both lock portion 6 and pivot 7. The rod 5 is normally 30 held in locked position or non-sliding, as pivot 7, having handle 8, is slightly turned or jammed in the lock portion 6 by reason of spring 9 pressing against the pivot arm or handle 8, Fig. 2, and holding it at an angle, 35 so that the perforation in pivot 7 is out of alinement with the perpendicular bore of lock portion 6, and there being no clear or unbroken passage the rod 5 cannot move up or down, but remains jammed or in fixed position. The rod 5 being of one piece with or 40 secured to arm 4, which latter is attached to the window-sash 1, the latter will be firmly held at a height relative to the position of rod 5 when it is locked. Arm 4 has at its 45 outer end an eye 4', so that it can slide along guide-rod 10, and around which rod is coiled spring 11, which furnishes the power for the automatic operation of the window.

Both sashes are operated in like manner, 50 the arm 4 of the lower sash 1' also being provided with an arm or bracket 4, differing from the arm 4 of the upper sash by having a de-

pending shank 12, Fig. 5, so that the eye part 4' is dropped or carried to the lower part of sash 1', and a spring 11 of some length can 55 be used for such lower sash, such spring 11 being shown connected to the eye part 4' on shank 12.

Fig. 1 shows both sashes in closed position, the power-springs 11 being drawn or extended. 60 When it is desired to open one or the other sash, button 8' is pressed against action of spring 9, so as to turn pivot 7 in lock portion 6, and thus bring the hole in said pivot in strict alinement with the perpendicular bore in lock 65 portion 6. This will free the lock bar or rod 5 and provide an unbroken passage for such rod, and the latter passing therethrough is forced along by the power-spring 11, together with the sash, so as to move up or down, and 70 when at proper height the pressure on button 8' is released, the handle 8 is held at an angle by spring 9, the pivot or clutch 7 is thereby jammed or moved, breaking the passage in lock portion 6, and the rod 5 is arrested and locked, and the window or sash is thus firmly held at the desired height. A slit 3', Fig. 3, is cut through or along the window-casing for the passage of neck 3, permitting the latter to move up and down. 80

The guide-rods 10 or their carriers 14 are fixed or secured to suitable parts of the casing, as are also the tubes or lock portions 6. The springs 11 can be of such strength or tension as to move the sashes, or such springs 85 could be arranged to simply hold or counter-balance the sashes, so that the latter can be easily moved by hand. Antifriction-rollers 15 opposite the brackets 2 can be made to ease the travel of the sashes. The bracket 2, 90 with its locking-rod 5 steadied by the guide or eye 6, in connection with the guide-rod 10, tends to keep the sash steady or leveled, so that with ordinary weight-sashes the anti-friction-rollers 15 will not be needed. The 95 closure of the sashes is effected by hand, while on pressing one or another of buttons 8' either the lower sash will rise or the upper sash drop to open the window. The lock 67 can act at any point to lock a sash when 100 closed, open, or partly open. A relief-spring 16 on rod 5 can cause the opening sash to be gradually arrested. To prevent the arm 4 wearing the woodwork in its motion such

woodwork could be reinforced by brass or metal. The buttons 8' could be adjustably connected to rods 8 or such rods made adjustable or extensible to set the buttons at desired heights.

What I claim as new, and desire to secure by Letters Patent, is—

1. The combination with a sash, of a bracket secured thereto, a spring acting on a part of the bracket, a locking-bar extending from the bracket, and a lock through which the locking-bar slides longitudinally and by which said bar is locked in any desired position, substantially as described.
- 15 2. A sash having a bracket, a spring connected to the bracket, a locking-bar, a clutch, and a spring normally holding the clutch in locking position substantially as described.

3. The combination with a sash, of a bracket secured to one corner thereof and provided with a vertical locking-bar and a projecting guide-arm, a guide-rod on which the said guide-arm moves, a spring arranged on the guide-rod and acting against the guide-arm, and a lock through which the said locking-bar slides longitudinally and by which said bar is locked in any desired position, substantially as described.

In testimony whereof I have hereunto set my hand in the presence of two subscribing witnesses.

JOSEPH A. MANAHAN.
